Filed Dec. 21, 1972, Ser. No. 317,284

Term of patent 14 years

Int. Cl. D21—01

U.S. Cl. D34—5 CC

FIG. 1 is a perspective view of a horseracing gameboard showing my new design with the horses in a typical racing arrangement and the winner's indicating block in a raised position;

FIG. 2 is a top plan view thereof with the horses in the starting position;

FIG. 3 is a side elevational view thereof;

FIG. 4 is an end elevational view as seen from the right side of FIG. 1; and

FIG. 5 is an elevational view of the opposite side of FIG. 4.

The side opposite of that of FIG. 3 is identical to that shown.

I claim:

The ornamental design for a horseracing gameboard, as shown and described.
